9 Claims. (Cl. 313—65)

1

This invention relates to television transmitting tubes and more particularly to the image analyzing screens of such devices in which a directive electron beam is employed for screen scanning.

It is an important object of the invention to provide a television transmitting tube having a novel form of image analyzing screen.

Still another object of the invention is to provide a television transmitting tube having an image analyzing screen which is simple and relatively inexpensive to manufacture.

According to the invention the above objectives are achieved, if in a television transmitting tube having a source of a directive electron beam, the image analyzing screen comprises a substance, the dielectric constant of which varies with variations in the intensity of the light projected onto the screen. This light sensitive substance in the device of invention is applied to an electrically conductive surface of a carrier, and the opposite side of this substance is coated with a thin layer of insulating material. The directive electron beam of the tube scans this thin layer of insulating material occasioning a varying potential differential across the light sensitive substance corresponding to the variations in the light intensity of the image formed on the screen. These potential variations are then converted to successive current variations which may be amplified in the well-known manner for transmission.

In order that the invention may be more clearly understood and readily carried into effect, it will now be described in detail with reference to the accompanying drawings, in which:

Fig. 1 shows diagrammatically a television transmitting tube in which the invention is used.

Fig. 2 is a fragmentary sectional view of the television transmitting tube of Fig. 1.

Referring to Fig. 1 the electrode system 1 produces a directive electron beam 2. The system 1 and the image collecting or analyzing screen 3 are housed in an exhausted glass vessel 4. The electrode system 1 is of a usual type and comprises an electron-emitting cathode 5, a Wehnelt electrode 6, a first anode 7 and a final anode 8. Use may be made of electro-static fields or of magnetic fields for focusing the beam 2 on the screen 3. For supplying the required voltages to the electrodes of the electrode system use may be made of a voltage source 9, the positive terminal of which is furthermore connected to a collecting electrode 10, which may preferably be in the form of a conductive coating on the tube wall 4. Such a coating may be a graphite de-

2

posit for example. In the particular embodiment shown, this electrode 10 is connected through a resistance 11 to the screen 3. By means of the optical lens 12 the image of an object 13 to be transmitted by the device is projected onto the image analyzing screen 3. The electron beam is deflected in directions at right angles to each other by means of the magnetic fields. As the deflection members required for this purpose, a couple of coils 14 are shown by which the beam is deflected at right angles to the plane of the drawing.

The projection screen 3 as shown more clearly in Fig. 2 consists of a transparent support 15 of insulating material, for example, of mica, to which is applied a thin transparent layer 16 of electrically conductive material. This layer 16 may consist of chromium, iridium or platinum and is termed the signal plate. It constitutes the common coating of the image analyzer system operating as a multiple capacitor. The dielectric 17 consists of a substance which is sensitive to actinic rays and of which the dielectric constant varies with the irradiation intensity. Known substances having this property are, for example zinc sulphide, cadmium sulphide, zinc selenide, cadmium selenide or a mixture of two or more of these substances. In the manufacture and working up of these materials methods already known in connection with sulphides and selenides may be utilised. Thus for increasing sensitivity, fluxes may be added, preferably fluxes which do not increase the conductivity of the substance, e. g. magnesium fluoride as already known the spectral sensitivity can be increased by a copper or silver addition. This dielectric is coated with an insulating layer 18. If this layer 18 is transparent, the image may be projected either onto one or onto the other side of the screen 3. The insulating layer should then be as thin as possible, in order that a maximum portion of the image producing rays may pass. However, the electrons of the beam are just prevented from passing. A layer thickness of approximately 0.2 μ is advantageous in this respect. This layer 18 may be, for instance, of silicon dioxide or other suitable material and the layer may be obtained by applying these substances by vaporisation.

The counter-coating co-operating with the signal plate 16 in the multiple capacitor system which forms the image-electrode is constituted by the point of impact of the electron beam 2 on the insulating layer 18. This point of impact has finite dimensions and, since the beam moves incessantly, the point of impact sweeps across the

surface of layer 18. For purposes of illustration it may be assumed that the beam spot stays for an instant at the point indicated in Figure 2. By means of the voltage source 9 the electron velocity may be adjusted in a manner such that the number of secondary electrons released at the point of impact of the beam on the layer 18 exceeds the number of primary electrons in the beam striking the screen. Consequently, the secondary-emission coefficient exceeds unity. Initially, substantially the whole secondary-emission current is carried off to the collecting electrode 10, so that the potential of the surface area on the layer 18 struck by the beam increases. This potential increase which amounts to a few volts, produces a counterfield relative to the collecting electrode 10, so that gradually fewer electrons are carried off to the latter. Apart from the electrons wandering to the collecting electrode, part of the secondary-emission electrons spreads over the surface of the insulating layer 18. These electrons cause the potential of this surface to decrease to a value slightly lower than the potential of the collecting electrode. In this manner a potential jump which, at a constant electron velocity is uniform for any point of the surface, occurs at the surface struck by the beam relative to the remaining part thereof. Consequently, the variation of the electric charge of each capacitor element thus produced depends upon the capacity of the image element i. e. upon the dielectric constant of the beam-sensitive substance at this area. The latter varies with the intensity of exposure and increases as the intensity of the light of exposure increases, with the result that the electric charge also increases. Consequently, an electric current is produced across the connection between the signal electrode 16 and the collecting electrode 10, the variations of which current correspond with the charge variations and consequently with the dielectric constant variation. This current produces across the resistance 11 a voltage which is supplied to the grid of the amplifying tube 19.

It is evident that with a beam swinging continuously across a continuous surface, the supply of the electric charge by the beam and its levelling by electron-spread over the surface with varying exposure, show themselves in the mean value of the signal current through the resistance.

What I claim is:

1. A television tube for the transmission of images comprising an envelope, a source of a directive beam of electrons within said envelope, a collecting electrode spaced from said beam source, and an image screen within said envelope and spaced from said collector electrode and in the path of said directive electron beam, said screen comprising a body portion of a substance having a variable dielectric constant responsive to light intensity variations, an insulating coating portion on the side of said body portion facing said electron beam source, and a support portion on the side of said body portion remote from said electron beam source and having an electrically conductive surface contacting said body portion.

2. A television tube for the transmission of images comprising an envelope having a light transparent portion, a source of a directive beam of electrons within said envelope, a collecting electrode spaced from said beam source, and an image screen within said envelope and spaced from said collector electrode and in the path of said directive electron beam and exposed to light from said transparent portion, said screen comprising

5 a body portion of a substance having a variable dielectric constant responsive to light intensity variations, an insulating coating portion on the side of said body portion facing said electron beam source, and a support portion on the side of said body portion remote from said electron beam source and having an electrically conductive surface contacting said body portion.

3. A television tube for the transmission of images comprising a glass envelope, a source of a directive beam of electrons within said envelope, a conductive coating collecting electrode on said envelope wall and spaced from said beam source, and an image screen within said envelope and spaced from said collector electrode and in the path of said directive electron beam, said screen comprising a body portion of a substance having a variable dielectric constant responsive to light intensity variations, a thin insulating coating portion on the side of said body portion facing said electron beam source, and a light transparent portion on the side of said body portion remote from said electron beam source and having an electrically conductive surface contacting said body portion.

4. A television tube for the transmission of images comprising a glass envelope, a source of directive beam of electrons within said envelope, a collecting electrode spaced from said beam source, and an image screen within said envelope and spaced from said collector electrode and in the path of said directive electron beam, said screen comprising a body portion of a mixture of substances each of said substances having variable dielectric constant responsive to light intensity variations, an insulating coating portion on the side of said body portion facing said electron beam source, and a support portion on the side of said body portion remote from said electron beam source and having an electrically conductive surface contacting said body portion.

5. A television tube for the transmission of images comprising a glass envelope, a source of a directive beam of electrons within said envelope, a collecting electrode spaced from said beam source, and an image screen within said envelope and spaced from said collector electrode and in the path of said directive electron beam, said screen comprising a body portion of zinc sulphide having a variable dielectric constant responsive to light intensity variations, a thin insulating coating of silicon dioxide on the side of said body portion facing said electron beam source, and a light transparent portion on the side of said body portion remote from said electron beam source and having an electrically conductive surface contacting said body portion.

6. A television tube for the transmission of images comprising a glass envelope, a source of a directive beam of electrons within said envelope, a collecting electrode spaced from said beam source, and an image screen within said envelope and spaced from said collector electrode and in the path of said directive electron beam, said screen comprising a body portion of cadmium sulphide having a variable dielectric constant responsive to light intensity variations, a thin insulating coating of silicon dioxide on the side of said body portion facing said electron beam source, and a support portion on the side of said body portion remote from said electron beam source and having an electrically conductive surface contacting said body portion.

7. A television tube for the transmission of images comprising a glass envelope, a source of

a directive beam of electrons within said envelope, a collecting electrode spaced from said beam source, and an image screen within said envelope and spaced from said collector electrode and in the path of said directive electron beam, said screen comprising a body portion of zinc selenide having a variable dielectric constant responsive to light intensity variations, a thin insulating coating of silicon dioxide on the side of said body portion facing said electron beam source, and a light transparent support portion on the side of said body portion remote from said electron beam source and having an electrically conductive surface contacting said body portion.

8. A television tube for the transmission of images comprising a glass envelope, a source of a directive beam of electrons within said envelope, a collecting electrode spaced from said beam source, and an image screen within said envelope and spaced from said collector electrode and in the path of said directive electron beam, said screen comprising a body portion of cadmium selenide having a variable dielectric constant responsive to light intensity variations, a thin insulating coating of silicon dioxide on the side of said body portion facing said electron beam source, and a light transparent portion on the side of said body portion remote from said electron beam source and having an electrically conductive surface contacting said body portion.

9. A television tube for the transmission of images comprising a glass envelope, a source of

directive beam of electrons within said envelope, a conductive coating collecting electrode on said tube envelope surrounding the path of said directive beam and spaced from said beam source, and 5 an image screen within said envelope and spaced from said collector electrode and in the path of said directive electron beam, said screen comprising a body portion of a mixture of zinc sulphide and cadmium sulphide having a variable dielectric constant responsive to light intensity variations, a thin insulating coating of silicon dioxide on the side of said body portion facing said electron beam source, and a light transparent support portion on the side of said body portion remote from said electron beam source and having an electrically conductive surface contacting said body portion.
